UNITED STATES PATENT OFFICE.

JOSEPH S. WILLIAMS, OF RIVERTON, NEW JERSEY.

RESILIENT ANNULAR BODY.

1,391,151.

Specification of Letters Patent. Patented Sept. 20, 1921.

Original application No. 761,192, filed April 15, 1913. Divided and this application filed December 20, 1917. Serial No. 208,037.

To all whom it may concern:

Be it known that I, JOSEPH S. WILLIAMS, of the United States of America, residing at Riverton, in the county of Burlington, State 5 of New Jersey, have invented a new and useful Resilient Annular Body, of which the following is a specification.

My present invention is a division of my copending application Serial No. 761,192, 10 filed April 15, 1913.

My invention also relates to the method of forming and combining the elements of tension and resilient supports in an annular body, and supporting such body in and 15 about an inner support and in and about the periphery of a wheel whereby the load will be resiliently supported and balanced.

My invention further relates to the method of forming a universally resilient 20 noncollapsible annular body so that it will be normally resilient and load sustaining, and so that the stability, resiliency, capacity and efficiency of the construction will be increased and strains will be distributed and 25 balanced by the body in the state of resiliency tension.

The object of my invention is to provide a resilient annular body of novel construction, which as a unit of structure, can readily 30 be applied to or demounted from the rim of the wheel, and which will resiliently support and balance load, thrusts and reactions, and which will be non-collapsible and 35 inflatable and be universally resilient and operate as an endless resilient tension truss, and as an annular body of resilient tension.

It is a further object of this invention to provide an annular body of resilient construction in which the elements of tension 40 and resilient supports are so disposed and combined and in such formation, annularly and transversely in a unit of operative construction, as to be universally resilient and load sustaining outwardly of and when combined in tension with and about an annular and transverse inner trussing support, and about which the terminals of annular and transversely disposed tension belt of the body are securely anchored.

Other objects and advantages of my invention will hereinafter appear in the detailed description.

For the purpose of illustrating my invention, I have shown in the accompanying drawings a typical embodiment of it which

is at present preferred by me, since this embodiment will give in practice satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a side elevation partly 60 in section of a resilient wheel equipment embodying my invention, the same being shown in assembled condition with respect to a vehicle wheel.

Fig. 2 represents a transverse section of a 70 portion of Fig. 1, taken through the upper part of the construction.

Fig. 3 represents a transverse section of a portion of Fig. 1, showing the lower portion of the construction.

Fig. 4 represents a side elevation partly 75 in section of a portion of a wheel equipment embodying my invention.

Fig. 5 represents, in perspective, a transverse section of Fig. 4, the section being 80 taken through the upper portion of the construction.

Fig. 6 represents, in perspective, a transverse section of a portion of Fig. 4, showing the lower portion of the construction.

Similar numerals of reference indicate 85 corresponding parts in the figures.

Referring first to Figs. 1 to 3 inclusive, 1 designates a tread, having its inner periphery circumferentially and transversely 90 disposed, and with a radially projecting tread wearing part extending therefrom to the tread surface, which latter may have any desired contour, although in practice the same is preferably made substantially 95 concentric with the resilient and tension elements of the annular body of the construction, inwardly thereof and supporting this tread. The tread is shown with curvature toward the sides thereof, and carried by and secured to an outer annular and transversely disposed tension belt 2, consisting of longitudinal and transverse tensile material, such as fabric or the equivalent in combination with vulcanized rubber. A breaker strip 100 3 of resilient rubber and tensile material is shown in vulcanized combination on the inner face of the tensile belt 2.

The tread and the tensile belt 2 are inwardly supported upon the outer periphery 110

of the breaker 3, and a layer of rubber 4, which extends about the sides and incloses an annular and transversely disposed resilient trussing and cushioning portion 5, 5 consisting of rubber or layers of fabric and rubber vulcanized together, and supported on an inner annular and transversely disposed tension belt 6, of flattened arch formation in transverse cross section, with sides 10 of such belt curved and extending inwardly and laterally, in close curvature formation about an annular and transversely disposed inner trussing, and thrust transmitting portion 10. The tension belt 6, is shown with 15 the flattened arch formation in spaced relationship to the major transverse axis 7, of the construction, with inner annular and transversely disposed cushioning and inflatable support 8. The sides 9, of belt 6 extend in tension about the sides of 8, and 20 an annular and transversely disposed inwardly channeled trussing and thrust transmitting member 10, to terminal parts 11, which are securely anchored to maintain 25 the belt 6, in tension about such supports.

A transversely divided annulus 12, with an outer face, co-fittable under expansion against the inner faces of the terminal parts 11, and interlockable by means of engaging 30 parts 13 thereof, with the parts 14, on the inner face of 10, prevents relative circumferential movement of the parts.

The transversely divided member 12, is 35 also shown with locking parts 15, on the inner face to co-lock with suitable parts on the fixed rim of the wheel when the member 12, shall be sufficiently expanded against the terminals 11 and outer seating parts to provide for placing or forcing the equipment on the rim 21 of the wheel, shown in 40 Figs. 1 and 4. The outer periphery of the member 10, is incavated or inwardly curved as at 16, in order to form with a resilient support 8, a clearance space 17, which latter may be provided, if desired, with elastic, 45 mobile fluid or filling content, although the same may be dispensed with in many cases arising in practice. The resilient support 8, is preferably formed of rubber or alternate layers of fabric and rubber in vulcanized combination, and is provided with the inwardly extending portion 16, in order to form the fluid tight tube 19 which contains the clearance space 17. The sides of the 50 inner tensile belt 6 are in close curvature formation around the sides of 8, and the sides of 10, and form stable abutments therewith. The member 12, provided with transversely disposed locking parts 15, 55 adapted to interlock with parts 20 on the felly band 21, prevents relative circumferential movement of the parts. The lateral movement is prevented by means of clips 60 secured to the felly 22, by means of fastening devices 23. The outer tensile belt 2

is substantially concentric with the inner tensile belt 6 and with the resilient trussing support 8, inwardly thereof, and resilient trussing support 5, and breaker 3 to the tread 1, outwardly thereof. The sides 70 of such annular body of the resilient trussing construction extend laterally beyond the width of road contact of the tread and thereby provide a large area of resilient and trussing support for tread, and otherwise 75 for the body between the inner thrust transmitting trussing and seating portions—comprising the members 10 and 12 and parts therebetween and inwardly thereof, to the axis of wheel and the parts of the body 80 outwardly thereof to the road.

Referring now to the embodiment seen in Figs. 4 to 6 inclusive, the results attainable are substantially the same as in the construction just described with reference to 85 Figs. 1 to 3 inclusive, but in the embodiments seen in Figs. 4 to 6 inclusive, the resilient trussing and cushioning support 23, between the tension belt 2, and the tensile belt 6, is provided with pores or cells 24. 90

The pores or cells are shown disposed in annular and transversely disposed layers of vulcanized rubber reinforced by annular and transversely disposed layers or belts of flexible fabric of open weave or the equivalent thereof, in the form of circumferentially disposed cords and transverse cords, in combination with vulcanized rubber, whereby such formation in vulcanized combination with the inner belt 2 and its 100 terminal portions 11 and the belt 6, and parts outwardly thereof, including the tread will operate as a universally resilient non-collapsible truss when mounted on the member 10. 105

Figure 1 shows my construction as in Figs. 3 and 4 mounted in wheel equipment,—the arc lines 25—26 and 27 represent the ranges of one-quarter, five-sixteenths and three-eighths of an inch respectively. 110

Fig. 4 shows construction as in Figs. 5 and 6 with the wheel omitted from the rim.

By reference to Figs. 1 and 4 and the transverse sectional views 2—3—5 and 6, it 115 will be seen that the longitudinal and transverse tension in the belts in the construction provide continuous annular and transverse tension support in combination with the resilient support in vulcanized combination, 120 throughout the depth and width of the annular body.

The inner inflatable and trussing portion in the spacing between the inner tension belt and the inner annular and transverse trussing member about or with which the tension belt is secured can be formed with or as unit part of the body or be removable therefrom. 125

In all the embodiments, "tension belt of 130

flattened arch formations," consists of an annular and transverse tensile material in combination with vulcanized rubber, with such standard of strength as required for any 5 special size and character of construction and the strains to which it may be subjected.

The construction provides a universally resilient and non-collapsible annular body which will be absolutely stable in wheel 10 equipment, and provides for resiliently supporting and balancing load and thrusts so as to secure flexing and flattening action along the plane of road contact of 20° to 25° slightly more or less, and a corresponding 15 range of altitude of one-quarter to three-eighths of an inch as clearly shown by the drawings.

While the embodiments clearly show such standards of capacity and resiliency, in tensile and resilient trussing, as inherent in the construction, it will be obvious that by means of suitable mobile content under suitable pressure in the clearance space of fluid tight tube between the belt 6 and the member 25 10, the entire annular body of resilient construction can be placed under any desired degree of tension so that such body will function as a universally resilient truss in tension about the periphery of the wheel.

30 The tension belt in flattened arch formation is resiliently and positively trussed annularly and transversely so that the sides of such arch formation are flexible on side abutment supports, and firmly secured therewith. This tension belt consists of annular and transverse tensile material in combination with vulcanized rubber, with such standard of strength as required for any special size and character of construction 35 40 and the strains to which it may be subjected.

The clearance space or fluid tight tube between such arch formation and the inner support permits of the desired flexing of the arch formation transversely and annularly. 45 The annular and transverse trussing and cushioning portion, cellular or otherwise as shown, and the outer belt and tread all operate as an annular resilient tension trussing portion for the flattened arch formation 50 of the inner tension belt and therethrough to the side abutment supports.

When the construction is submitted to load from the axis of the wheel, the stresses are distributed by the rims to the annular inner 55 trussing support and to the side abutments of the flattened arch and are taken up and distributed by the transverse tension about the side abutments and by the longitudinal tension of such arch formation to and 60 through the annular and transverse trussing and cushioning portion and belt and the tread outwardly thereof. The tread and body flex annularly and transversely in proportion to such strains, and the capacities 65 of the construction,

By means of air or other suitable mobile content under pressure within the annular clearance space, it is not only practical to provide any desired load capacity or standard of balance in the construction but to 70 compensate or even neutralize the compressive strains, by placing the body in a suitable degree of resilient tension.

Having thus described my invention, what I desire to secure by Letters Patent is:— 75

1. A resilient annular body comprising an annular and transversely elongated innermost portion bisected by the major transverse axis, of flattened arch formation in transverse cross section outwardly of said axis, with curvatures about the sides and inwardly of the seating parts, an annular and transversely disposed flexible tension belt in and about said flattened arch formation and in curvatures about the sides to 85 the seating parts, an annular and transversely disposed resilient supporting trussing portion bonded with and encircling said tension belt, an outer annular and transversely disposed outermost tension belt 90 bonded with and encircling said resilient trussing portion, and a tread wearing part encircling and supported by said outermost tension belt.

2. A resilient annular body comprising an annular and transversely elongated innermost portion bisected by the major transverse axis, of flattened arch formation in transverse cross section outwardly of said axis, with curvatures about the sides and inwardly of the seating parts, an annular and transversely disposed flexible tension belt in and about said flattened arch formation and in curvatures about the sides to the seating parts, an annular and transversely disposed resilient supporting trussing portion bonded with and encircling said tension belt, an outer annular and transversely disposed outermost tension belt bonded with and encircling said resilient trussing portion, 100 105 a tread wearing part encircling and supported by said outermost tension belt, an inner annular and transverse trussing member extending across said innermost portion and supporting and trussing the inner walls 110 and seating parts of the tension belt of said innermost portion across and inwardly of said major transverse axis, and a resilient support about the periphery of said inner annular and transverse trussing member 115 forming abutment supports for the curvatures of said inner tension belt.

3. A resilient annular body comprising an annular and transversely elongated innermost portion bisected by the major transverse axis, of flattened arch formation in transverse cross section outwardly of said axis, with curvatures about the sides and inwardly of the seating parts, an annular and transversely disposed flexible tension 125 130

belt in and about said flattened arch formation and in curvatures about the sides to the seating parts, an annular and transversely disposed resilient supporting trussing portion bonded with and encircling said tension belt, an outer annular and transversely disposed outermost tension belt bonded with and encircling said resilient tension portion, a tread wearing part 10 circling and supported by said outermost tension belt, an inner and transverse trussing member extending across said innermost portion and supporting and trussing the inner walls and seating parts of the tension belt 15 of said innermost portion inwardly of said major transverse axis, a resilient support about the periphery of said inner annular and transverse trussing member forming abutment supports for the curvatures of the 20 inner tension belt, and means to vary the pressure between said belt and said inner trussing support and the tension upon the body.

4. A resilient annular body comprising an 25 annular and transversely elongated innermost portion, bisected by the major transverse axis and having therein an annular and transverse trussing and thrust transmitting member located crosswise of said portion inwardly of said axis and having a channel formation between the sides thereof; a resilient support about the periphery of said member including a fluid-tight 30 annular passage and an annular and transversely disposed flexible tension belt in tension about said support and member with curvatures in close formation therein about the sides and extending to seating parts, and anchorage inwardly of said trussing member 35 and having outwardly of said innermost portion and bonded therewith an annular and transversely disposed outer resilient trussing portion bonded with said innermost portion, and extending outwardly with diminishing width toward the outer periphery of the body, and having in such outermost portion a resilient annular and transverse trussing portion next said innermost portion a tension belt encircling said annular and transverse trussing portion and a belt of tread material encircling said tension belt.

5. A resilient annular body comprising an 55 annular and transversely elongated innermost portion, bisected by the major transverse axis, and having therein an annular and transverse trussing and thrust transmitting member located crosswise of said portion inwardly of said axis and having a channel formation between the sides thereof; a resilient support about the periphery of said member including a fluid-tight annular passage and an annular and transversely disposed flexible tension belt in tension about said support and member with 60 curvatures in close formation therein about

the sides and extending to seating parts and anchorage inwardly of said trussing member; and having outwardly of said innermost portion and bonded therewith an annular and transversely disposed outer resilient trussing portion bonded with said innermost portion, and extending outwardly with diminishing width toward the outer periphery of the body, and having in such outermost portion a resilient annular and transverse trussing portion next said innermost portion a tension belt encircling said annular and transverse trussing portion and belt of tread material encircling said tension belt and a filling in said fluid tight 75 passage under pressure.

6. A demountable annular equipment, comprising an endless annular body having an inner, annular and transverse trussing portion provided with a seating and side 85 abutments, an outer annular and transverse tension trussing portion transversely disposed in flattened arch formation relatively to the major axis of the body in cross section, and having its sides extending around said abutments and anchored in tension about and to said inner trussing portion, said inner and outer trussing portions having disposed between them means to provide for the flexing movements of said outer 90 tension trussing portion, an annular resilient trussing portion bonded with and about said tension trussing portion, an annular tension belt about said means between said side 95 abutments forming annular and transverse seating support in forced engagement with the inner peripheral parts of the body and forming therewith a demountable annular unit of structure.

7. A demountable annular equipment, 105 comprising an endless annular body having an inner, annular and transverse trussing portion provided with a seating and side abutments, an outer annular tension trussing portion transversely disposed in flattened arch 110 formation relatively to the major axis of the body in cross section and having its sides extending around said abutments and anchored to said inner trussing portion, said inner and outer trussing portions having disposed between them means to provide for the flexing movements of said outer tension trussing portion, an annular resilient trussing portion bonded with and about said tension trussing portion, a tension belt bonded 115 with and about said resilient trussing portion, a tread, an inner support between said side abutments about the inner peripheral parts of the body and forming therewith a demountable unit of structure, and means to 120 vary the tension, resiliency and capacities of the body.

8. A demountable annular equipment, comprising an endless annular body having an inner annular and transverse truss 125

- formed of an annular inextensible member with channeled outer face between the sides thereof, an outer annular and transverse tension trussing portion disposed in flattened arch formation relatively to the major axis of the body in cross section and having its sides deflected around and inwardly of said inner truss, a resilient annular and transverse trussing portion bonded to said tension trussing portion, a tread, and means to compress the terminals of said outer trussing portion against said inner truss, to form a unit of structure, co-fittable in wheel equipment.
- 15 9. A demountable annular equipment, comprising an endless annular body having an inner annular and transverse truss formed of an annular inextensible member, an outer annular and transverse flexible tension trussing portion disposed in flattened arch formation relatively to the major axis of the body in cross section and having its sides deflected around and inwardly of said inner truss, an annular tension and transverse resilient trussing portion bonded to said tension trussing portion, an annular flexible tension belt bonded with and about said resilient trussing portion, a tread, an inner support engaging the inner peripheral parts 30 of the body between said side abutments and maintaining the body in tension thereby and forming therewith a demountable annular unit of structure.
10. A demountable annular equipment, comprising an endless annular body having an inner and transverse annular truss formed of an annular inextensible member, an outer annular and transverse flexible tension trussing portion disposed in spanning 40 relationship across the direct lines of thrust and in spaced relationship to the major axis of the body in cross section and having its sides deflected in curvatures around the sides and inwardly of said inner truss, an annular resilient trussing portion bonded to said tension trussing portion, a flexible tension belt encircling said resilient trussing portion, and a tread.
11. A demountable annular equipment, comprising an endless annular body having an inner annular and transverse truss formed of an annular inextensible member, an outer annular and transverse tension trussing portion disposed in flattened arch 55 formation relatively to the major axis of the body in cross section and having its sides deflected around and inwardly of said inner truss, an annular tension belt bonded to said outer tension trussing portion, an annular 60 and transverse resilient support and truss-
- ing portions bonded with and about said tension trussing portion, a tension belt about said support, a tread, annular reinforcements in the terminals of said outer tension trussing portion, and means to compress and 65 anchor the terminals of said tension trussing portion against said inner truss to form a unit of structure.
12. A demountable annular equipment, comprising an endless annular body having an inner annular and transverse truss formed of an annular inextensible member, an annular and transverse tension trussing portion disposed in flattened arch formation relatively to the major axis of the body 70 in cross section and having its sides deflected around and inwardly of said inner truss and transverse resilient support, a resilient trussing support between said inner truss and said tension truss an outer 75 resilient, annular and transverse trussing support, bonded with and about said tension truss, an annular tension belt bonded to said outer trussing portion, a tread, an expandable annular and transverse inner seating 80 support expanded against said body, and locking devices coöperating with said member and said inner tension truss to clamp and maintain the terminals of the tension 85 trussing portion in tension in assembled unit 90 of structure.
13. A demountable annular equipment, comprising an endless annular body having an inner annular and transverse truss formed of an annular inextensible member, 95 an annular and transverse tension trussing portion disposed in flattened arch formation relatively to the major axis of the body in cross section and having its sides deflected around and inwardly of said inner truss, a resilient trussing support between said inner truss and said tension truss bonded with 100 and about said tension truss, a tension belt bonded with and about said resilient trussing support, an annular tension belt bonded to said outer trussing portion, a tread, an inner support about the inner peripheral parts of said body, locking devices coöperating 105 with said inner support and said inner tension truss to clamp and maintain the terminals of the tension trussing portion in tension in assembled unit of structure, and means for changing and maintaining standards of internal pressure and tension of the body.
